A technical drawing of a tapered probe tip. The tip is labeled with the letter **P**. The main body of the probe is labeled with the letter **Q**. The base of the probe is labeled with the letter **R**. There are two small rectangular features on the side of the probe, each labeled with the letter **S**. The drawing is done in black and white with some shading to indicate depth.

UNITED STATES PATENT OFFICE.

JOHN P. LANCASTER, OF GOSHEN, INDIANA.

CAR-COUPING.

SPECIFICATION forming part of Letters Patent No. 271,085, dated January 23, 1883.

Application filed November 8, 1882. (No model.)

To all whom it may concern:

Be it known that I, JOHN P. LANCASTER, a citizen of the United States, and a resident of Goshen, in the county of Elkhart and State of Indiana, have invented a new and valuable Improvement in Car-Couplings; and I do hereby declare that the following is a full, clear, and exact description of the construction and operation of the same, reference being had to the annexed drawings, making a part of this specification, and to the letters and figures of reference marked thereon.

Figure 1 of the drawings is a vertical sectional view of my car-coupling. Fig. 2 is a front view of the coupling-pin detached from the draw-head. Fig. 3 is a side view, and Fig. 4 is a top or plan view, of the same.

This invention has relation to automatic car-couplers; and it consists in the construction and novel arrangement of devices hereinafter set forth, and particularly pointed out in the claim appended.

In the accompanying drawings, the letter A designates a draw-head, whereof B is the link-chamber, having a slot, C, extending longitudinally in its top, and D is an upper chamber above the slotted top, having an open front and bearings E in the front edges of its side walls. In the rear wall of the cavity of the draw-head 30 which receives the link are formed transverse recesses *g* and *g'* above and below a transverse rib, *h*. Projecting lugs *l* on the top of the upper chamber of the draw-head are formed with oblique slots *k*, forming bearings for the journals *m* of the angular fastening *N*, said journals being kept in position by the removable pins or screws *n*. When the angular fastening is in place its toe is engaged with a recess, *r*, in the top *t* of the draw-head in front of the chamber D.

P represents the T-shaped coupling-pin, which is formed with a cross-head, *a*, and a depending portion, *b*, the rear edge of which is in its lower portion curved in convex form, as indicated at *c*. To place the pin in position in the draw-head the fastening *N* is removed, the pins or screws *n* having been withdrawn from its bearings, and the depending portion of the pin is passed through the open front of the upper chamber, down through the slot C into the

link-chamber, the arms or journals *z* of the cross-head engaging the seats or bearings E at the front of the chamber D. Then the fastening *N* is replaced and secured in position, and it serves to prevent the pin from being casually removed from the draw-head. The cross-head of the pin is provided with a depending lateral arm, *G*, which hangs downward at the side of the draw-head, and is designed to be connected by a cord or chain, *e*, to a lever conveniently attached to the car, so that the pin can be vibrated backward to liberate the link in uncoupling. The cavity of the draw-head is enlarged back of the beveled mouth *M*, above and below, and the shoulders *m* form strong abutments for the pin. The lower shoulder also serves as a fulcrum on which the link may rest, its rear end being held against the bottom of the cavity by the convex rear edge of the pin, so that the outer end of the link is held in a raised position to couple with a high draw-head; or the link may be pushed back to engage the upper recess, *g*, or the lower recess, *g'*, at the back of the link-cavity, and may thus be held with its outer end in a depressed or raised position.

When the end of a link enters a coupler of this character the pin will be vibrated backward until the end of the link passes under its lower extremity. The pin will then swing forward through the slot of the link into the position of engagement.

Having described this invention, what I claim, and desire to secure by Letters Patent, is—

A draw-head having an open-front upper chamber, D, above the link-chamber, and communicating therewith by the longitudinal slot C, in combination with the removable T-shaped swinging pin P, journaled at the open front, as shown, and the removable fastening N, substantially as specified.

In testimony that I claim the above I have hereunto subscribed my name in the presence of two witnesses.

JOHN P. LANCASTER.
